By *John H. Phillips*
JAN 1923

UNITED STATES PATENT OFFICE.

JOHN H. PHILLIPS, OF CHICAGO, ILLINOIS.

EXPANSION SHELL.

Original application filed July 14, 1919, Serial No. 312,242. Divided and this application filed March 31, 1921. Serial No. 457,255.

To all whom it may concern:

Be it known that I, JOHN H. PHILLIPS, a citizen of the United States, residing at Chicago, in the county of Cook and State of Illinois, have invented certain new and useful Improvements in Expansion Shells (Case B), of which the following is a description.

This application is a divisional case of my application, Serial No. 312,242, filed July 10 14, 1919, patented May 24, 1921, Number 1,379,210.

My invention belongs to that general class of devices known as expansion shells, and relates particularly to a multi-part shell which 15 may be employed to drill two or more holes in concrete, brick, stone or like material, and then be separated and have each of its shell parts used with other parts, not drill parts and of cheaper construction, to fasten and 20 hold various devices and mechanisms to said material.

Among the many uses to which expansion shells are put may be mentioned the fastening of pipe and wire systems and electrical 25 mechanisms and other equipment, etc., to walls, ceilings, and floors of concrete, brick, stone or like material.

My invention has among its objects the 30 production of an expansion shell of the kind described, that is simple, convenient, efficient, reliable, durable, inexpensive and suitable for use wherever found applicable. It has particularly among its further objects to provide a shell made in two parts, and of 35 which one of said parts may be constructed as a drill part and the other part not a drill part, and of such construction that the drill part of one shell will pair with the drill part of another shell to form a complete tubular 40 drill, retaining the features essential to most rapid and economical drilling of two or more holes, after which the drill parts are paired with shell parts, not drill parts, and used as fastenings in the holes so drilled. An- 45 other object of this construction is that the non-drill part of cast metal or formed from sheet steel, insures an economical production of expansion shells of different design most suitable for fastening to different materials 50 and the most economical drilling of the holes in which they are permanently inserted.

A further object of my invention is to pro- 55 vide an interlocking means between the drill segment and the segment, not a drill seg-

ment, which will prevent any longitudinal displacement between said parts.

Another object of my invention is in some desired cases to provide an abutment on one of the shell parts which is adapted to be seated at the base of the hole in which it is 60 to be expanded, and which will engage a suitable expander to permit the shell to be effectively expanded.

Many other objects and advantages of the construction herein shown and described will 65 be obvious to those skilled in the art from the disclosure herein given.

To this end my invention consists in the novel construction, arrangement and combination of parts herein shown and described, 70 and more particularly pointed out in the claims.

In the drawings, wherein like reference characters indicate like or corresponding parts;

Fig. 1 is a sectional view taken through my improved shell, showing the expander in place;

Fig. 2 is a sectional view taken similar to Fig. 1, with the expander removed;

Fig. 3 is a sectional view similar to Fig. 2, showing the sections or parts separated;

Fig. 4 is a sectional view taken on the line 4—4 of Fig. 1; and

Fig. 5 is an end view of the separated parts shown in Fig. 3.

In the embodiment of my invention, as illustrated in the drawings, there is represented a tubular shell of the desired number of segmental parts, two being shown, said parts 1 and 2 being arranged circumferentially to form the complete shell, one of said parts, 1 for example, being preferably arranged with cutting teeth 4 at one end thereof. The parts are made of suitable material and of the desired size, part 2 being preferably made of much cheaper metal and in a cheaper fashion than part 1. This, however, is not essential. The untoothed end of part 1 is preferably tapered, as at 6, so as to be engaged by a suitable chuck, not shown. When forming the hole in the material 3, in which the parts are to be inserted, a pair of tubular drill parts, each fashioned like the segment 1, are engaged in a suitable chuck and then the hole drilled by any suitable mechanism which either reciprocates or rotates the drill parts.

The material of the drill is preferably so selected that it will drill two or more holes before it is too dulled for further drilling use, and then each drill segment is combined 5 with a cooperating segment 2, not a drill part, and of a cheaper material and structure, and inserted into the hole and expanded therein.

10 The member 2 has its lower end constructed, as at 6, so as to correspond with the chuck end of the part 1, in case the shell need at any time be engaged as an entirety by a chuck or the like.

15 The other end of the member 2 opposite its tapered end is offset to provide an end wall or abutment 9, which preferably fits within the open toothed end of the part 1, to substantially close said shell when assembled. Where two cast parts are employed, reduced 20 size extending parts similar to 9 may be placed on the two parts if desired.

25 Corrugations 8, or any other suitable manner of roughening, may be provided in the exterior of at least one of the parts, as for instance part 2, said corrugations being adapted to bite into and grip the wall of the hole in which the shell is inserted and expanded.

30 The bore of the shell plug is substantially circular except near the innermost or closed end 9. There the bore is inclined or conically tapered so that the bounding wall of the bore as it approaches the laterally projecting end wall 9 is of a larger cross section 35 than it is inwardly thereof. As shown, the segment 1 is bored or channeled with a circular arc entirely through its length, while the enlarged or channeled portion 10 of the part 2 may be of any desired contour, as 40 for instance, partly elliptical and tapered.

45 Adapted to be positioned within the bore is a cam-shaped member or nut 11, said nut being bored and threaded and eccentrically mounted on a bolt 12 having screw threads 50 13 thereon, said nut being of such a shape that a portion of its peripheral wall is circular, as at 14, so as to engage the circular bore of the part 1, and the remainder of its 55 peripheral wall is conically tapered, as at 15, and of the same degree of taper and curvature as the inclined tapered channel 10 of the part 2, so that the nut will be non-rotatable within the shell or plug but may be slid longitudinally thereof so as to expand the parts. The bolt and nut are placed into the bore before the shell parts are put into the hole, and when inserted into the hole the bolt 60 end will abut the end wall 9 of the part 2, and when screwed through nut 11 will cause the same to slide longitudinally to open or expand the shell parts into contact with the peripheral wall of the hole, safely holding the shell in place while permanent load is 65 applied to the rod or bolt 12.

The corrugations 8 will bite into the material in which the hole is made and tend to prevent any movement of the parts outwardly of the hole. The application of the permanent load or pull to the bolt will have 70 a further shell spreading action, thus firmly locking the parts in place in the hole.

I have not considered it necessary to illustrate the chuck by means of which the device is drilled, said chuck being described in my co-pending application, Serial No. 361,906, filed February 7, 1920, patented May 24, 1921, Number 1,379,209. It will be noted that the expansion shell and parts herein shown is especially applicable for fastening various devices to concrete ceilings and the like, requiring the use of round hangers or bolt connections, etc.

85 After the holes have been drilled to the desired depth, the chuck and drill shell removed, the drill parts are separated and each part 1 is mated with a cast shell part 2, and the tapered expander mechanism and bolt are then inserted in the bore of the shell and reinserted into the drilled hole. The expander is then operated to expand the shell parts, causing the same to be firmly and securely locked in place in the hole. To all intents and purposes, the same becomes substantially a permanent part of the wall, ceiling or the like, to which the various devices or other equipment may be secured by means of bars, rods, hangers, pins, bolts, nuts or the equivalent.

90 Having thus described my invention, it is obvious that various immaterial modifications may be made in the same without departing from the spirit of my invention; hence I do not wish to be understood as limiting myself to the exact form, arrangement, construction and combination of parts herein shown and described, or uses mentioned.

95 What I claim as new and desire to secure by Letters Patent is:

100 1. In an expansion shell of the kind described and in combination, a tubular plug arranged for expansion at one end, the bore of said plug at its expansible end having a portion of its surface bounded by a circular arc and the remainder bounded by another arc, said latter portion being tapered longitudinally of the bore, a nut arranged within said plug and having a portion of its peripheral surface bounded 105 by a circular arc which extends circumferentially for and less than the full periphery thereof, and by another arc completing said periphery, said latter portion being tapered longitudinally of the bore, whereby said nut and bore may have their similar surfaces in contact, and means for sliding said nut longitudinally of said bore.

110 2. In an expansion shell of the kind described and in combination, a tubular plug 115

- arranged for expansion at one end, the bore of said plug having a portion of its wall eccentric relative to the axis and tapered longitudinally thereof, a threaded bolt insertable within said bore, a nut eccentrically mounted on said bolt within said bore so that the eccentric nut wall engages the eccentric peripheral wall of said bore to expand said plug.
2. An expansion shell of the kind described, comprising a pair of circumferentially mating parts, one of said parts having a recess in its longitudinal edge and having cutting teeth at one end, the other of said parts having a projection on its longitudinal edge adapted to enter said recess and preventing relative movement therebetween.
3. An expansion shell of the kind described, comprising a pair of circumferentially mating parts, one of said parts having cutting teeth at one end, the other of said parts having a lateral wall at one end adapted to bridge the assembled shell at the toothed end, one of said parts having a recess in its longitudinal mating edge and the other of said parts having lateral projections on its longitudinal edge adapted to enter said recess and prevent relative movement therebetween.
4. An expansion shell of the kind described, comprising a pair of segmental parts one of which has cutting teeth and the other of which has no cutting teeth thereat, and means for expanding said shell.
5. An expansion shell comprising a pair of circumferentially arranged parts, one of which is a segmental part of a hollow drill and has cutting teeth thereon, and the other of which is a segmental part not a drill part and having no cutting teeth thereon, both of said parts being formed at one end to engage a chuck, and means for expanding said shell.
6. An expansion shell of the kind described comprising a tubular plug formed of a plurality of circumferentially mating members arranged for expansion at one end and having a laterally projecting end wall carried by only one of said members substantially closing one end of said bore, a bar insertable in said bore from its other end and adapted to abut said end wall, and means within said bore means cooperable with said bar to expand said plug.
7. An expansion shell of the kind described comprising a pair of circumferentially mating parts, one of said parts being open at both ends, and having no laterally extending wall at said ends, the other of said parts having a lateral wall at one end adapted to enter the open end of the cooperating segment and substantially close said end of the shell when assembled.
8. An expansion shell of the kind described, comprising a pair of circumferentially mating parts, one of said parts having cutting teeth at one end, the other of said parts having a lateral wall at one end adapted to bridge the assembled shell at the toothed end.
9. An expansion shell of the kind described, comprising a pair of circumferentially mating parts, one of said parts having cutting teeth at one end, the other of said parts having a lateral wall at one end adapted to bridge the assembled shell at the toothed end.

In testimony whereof, I have hereunto signed my name in the presence of two subscribing witnesses.

JOHN H. PHILLIPS.
